(57) **CLAIM**

The ornamental design for an extracorporeal shock wave machine, as shown and described.

DESCRIPTION

FIG. 1 is a top, front and right side perspective view of an extracorporeal shock wave machine, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2; and,

FIG. 11 is an enlarged view of portion 11 in FIG. 4.

The evenly broken lines show the features of the extracorporeal shock wave machine that form no part of the claimed design. The unevenly broken lines define the boundaries of enlarged views and form no part of the claimed design.
